[57] CLAIM

The ornamental design for a bottle, as shown and described.

DESCRIPTION

FIG. 1 is a perspective view of a bottle, embodying our new design;

FIG. 2 is a front elevational view thereof, the back elevational view thereof being the same;

FIG. 3 is a top view thereof; and,

FIG. 4 is a bottom view thereof.

The broken lines shown in the figures are for illustrative purposes only, and form no part of the claimed invention.
